UNITED STATES PATENT OFFICE.

JOHN F. KELLER, OF ST. LOUIS, MISSOURI.

DESIGN FOR A BADGE.

SPECIFICATION forming part of Design No. 23,884, dated December 25, 1894.

Application filed October 17, 1894. Serial No. 526,226. Term of patent 7 years.

To all whom it may concern:

Be it known that I, JOHN F. KELLER, of the city of St. Louis, State of Missouri, have invented and produced a new and original 5 Design for Badges, of which the following is a full, clear, and exact description, reference being had to the accompanying drawing, forming a part hereof.

The figure is a plan view or face of the de- 10 sign.

The leading feature of my design is the representation of a suitable ring confining a heart-shaped body showing the lobes of the heart.

15 Referring to the drawing, 1 represents an annular ring having a suitable inner and outer border with a plane or smooth surface or panel for any suitable lettering or motto. Depending from the inner circle of the ring 20 is a heart-shaped body 2, across which is

wound a thorn-wreath 3, the thorns piercing the heart, the parts 4 representing drops of blood flowing from the portion thus pierced. From between the lobes of the heart is a flaring base 5 from which emanate the flames 6, 25 the entire center piece being suspended by a ring 7.

The badge depends from a suitable bar 10, being secured thereto by the lugs 8 and chain pieces 9. 30

Having described my invention, what I claim is—

The design for a badge as herein described and shown.

In testimony whereof I affix my signature in the presence of two witnesses.

JOHN F. KELLER.

Witnesses:

H. A. UHL,
EMIL STAREK.
